CONTAINER AND METHOD OF MAKING
SAME

Kimberly Stuart, Menasha, Wis., and Allen B. Wilson, Evanston, Ill.; said Wilson assignor, by mesne assignments, to Elizabeth R. B. Stuart, Menasha, Wis.

Application April 9, 1941, Serial No. 387,736

6 Claims. (Cl. 229—5.7)

The present invention relates to containers and methods of making them, and more particularly to shipping cartons made of non-metallic sheet material reinforced by strengthening beads of metal or like material.

Although containers of reinforced fibrous material have been heretofore proposed, they have not been wholly satisfactory through failure to stand up under all conditions of service, especially when heavy goods are to be transported. Moreover, most of them have no appreciable strength unless the cover is tightly closed. In other words, they rely largely for strength upon a rigidly secured cover. Also, certain metal bound containers of the prior art are of complicated costly construction, which rules them out as commercially practical articles, and none of them is of sufficient strength to render them reusable, as, for instance, in delivery and return handling of beer, milk and other beverage bottles.

It is the major object of this invention to provide novel, low cost, reinforced non-metallic containers which are of maximum strength for the weight of fibre board and the quantity of reinforcing material incorporated in them, and which are so constructed that all of the edges of the board are protected by reinforcing material.

Another important object is to provide a container having a plurality of side walls formed from a single piece of board secured together at its ends and having a stiff, reinforcing bead at its top and bottom edges designed to rigidify the container and make it possible to handle heavy articles without serious distortion and also making it sufficiently rugged for use as a returnable milk or beverage case.

A further object is to provide a container having flat sides joined by rounded corners, and reinforcing beads or rims at the upper and lower edges of the sides operable to stiffen and protect the edges against scuffing and to also maintain the rounded form of the corners, thereby contributing two-fold to the rigidity of the container.

Another object is to provide novel top and bottom closure constructions for reinforced containers.

It is a further object to provide a novel method of making a container body from a single blank, out of which all the sides are formed, and top and bottom attaching members, the reinforcing beads being so applied that, when the container is set up, and before the top and bottom are applied, the sides and beads may be permanently secured in endless relationship.

A further object is to provide novel apparatus for bending rimmed blanks into curved form and so designed as to avoid collapse of the rims.

Another object is to provide a novel container of irregular hexagon shape, for packaging cylindrical articles with a minimum of voids between the articles and maximum utilization of the space within the container.

Further objects of the invention will become apparent as the specification proceeds in conjunction with the annexed drawings, and from the appended claims.

In the drawings:

Figure 1 is a perspective view of a container embodying the invention;

Figure 2 is a vertical transverse sectional view through the container of Figure 1, showing the parts on an enlarged scale;

Figure 3 is an enlarged sectional view taken substantially on line 3—3 of Figure 2, looking in the direction of the arrows;

Figure 4 is an enlarged fragmental perspective view of the corner of the container shown in Figure 1, but with the reinforcing band broken away to illustrate the joint between the two ends of the blank from which the sides are formed;

Figure 5 is an enlarged fragmental elevational view illustrating the joint shown in Figure 4; and with the hand and its connector in phantom lines;

Figure 6 is a bottom plan view of a corner of the container shown in Figure 1, on an enlarged scale;

Figure 7 is an isometric view of the blank from which the sides are formed and shows the blank with its flanges folded down, and with one of the strengthening beads applied;

Figure 8 is a fragmental sectional view of the upper edge of the container, showing a modified form of closure construction also forming part of the invention;

Figure 9 is an interior view of the container prior to applying the bottom wall, but shows a modified form of corner construction of the invention;

Figure 10 is a side elevational view of the apparatus preferably employed to bend the blank into finished form;

Figure 11 is a sectional view taken substantially along the line 11—11 of Figure 10;

Figure 12 is a horizontal sectional view through a hexagonal shaped container forming part of the invention;

Figure 13 is a fragmental perspective view, with parts broken away, of a container embody-

ng a modified bottom construction also forming part of the invention;

Figure 14 is a sectional view taken on the line 14—14 of Figure 13, looking in the direction of the arrows;

Figure 15 is a fragmental perspective view showing a modified top construction also forming part of the invention;

Figure 16 is a fragmental perspective view illustrating a container to which the rim or bead 10 is applied after it is set up, and

Figure 17 is a fragmental sectional view showing one manner in which the bead of Figure 16 may be applied to the container.

With continued reference to the drawings, 15 wherein similar reference characters have been employed to designate like parts through the several views thereof, and referring particularly to Figures 1-7, inclusive, the receptacle of the invention chosen for illustration is of rectangular shape, for packaging beer bottles or the like, but it is to be understood that the invention is not limited to any particular shape of receptacle and may be advantageously employed for producing receptacles of other shapes and sizes.

The container of the invention embodies flat sides 10, 11, 12 and 13 and rounded corners and is so designed as to take full advantage of the inherent rigidity and strength of a partial cylindrical surface and embodies reinforcing means for maintaining the cylindrical shape at the corners and for stiffening the flat sides of the unit, and for also protecting the edges against scuffing or other damage incident to rough handling in use. A hinged top or closure 14 and a bottom 15 complete the container.

The sides are preferably formed from a single length of material of any desired character, for instance fibre board of requisite weight. Referring to Figure 7, which illustrates a blank opened out, the blank terminates at one end in a square edge 16 and at the other in a flap 17. Flap 17 tapers into short, transversely disposed surfaces 18, for a purpose that will presently appear.

The blank is also provided with a plurality of flanges T1—T4, inclusive, and B1—B4, inclusive, which, as seen in Figure 7, are folded down flat against the body of the blank prior to the rimming operation. If desired, a pair of hand hole openings 21 may be provided in the blank prior to folding it into final form.

With the blank in the condition shown in Figure 7, with the flanges folded down, it is fed into a rimming device of any desired character, and a continuous metallic rim or reinforcing edge 22 is applied thereto. As seen in Figures 2 and 3, the rim is of C-shape in transverse section, and during the rimming operation sufficient pressure is applied to cause the rim to bite into opposite sides of the blank adjacent the edge, with the result that an extremely strong bond is formed between the rim and blank. A similar rim 23 is applied along the opposite edge of the blank. The rim or beads may be simultaneously applied to the opposite edges of the blank in a double rimming machine, or if desired the blank may be passed through the machine twice to rim both edges. A rimming machine which may be used to apply the rims to the blank is disclosed in United States Letters Patent No. 2,283,962 of Wilson and Swangren issued May 26, 1942. In either event, the rim-forming material is cut to lie substantially flush with edges 16 and 18 at the opposite ends of the blank, so that, when the latter is folded up in 75

container form, the opposite edges of the rims will be disposed in abutting relationship.

The blanks are preferably shipped in flat form, with the rims fastened to their opposite longitudinal edges. At the point of use, the blanks are folded up into container form, preferably by a roll form of bending apparatus to be hereinafter described, into the form shown in Figure 1, so as to have four corners 25 of partial cylindrical form. The radius of curvature of the corners may vary as desired, but if cylindrical articles are to be packaged, the corners will be given a radius of curvature corresponding substantially to the radius of curvature of the article, so that the maximum utilization of the material of the container may be made. By simultaneously rolling the sides and rim members 22 and 23 into partial cylindrical form, the corners maintain their shape and materially contribute to the strength of the unit, since they are inherently stable.

After the blank has been bent into the form just described, flap 17 is preferably brought outside wall 13, edges 18 are brought into alignment with edge 16, as seen in Figure 4, and flap 17 is rigidly secured to wall 13 by means of metal staples 27, but any other suitable fastening means may be employed.

With the parts disposed as just described, the opposite ends of rims 22 and 23 will be disposed 30 slightly out of lateral alignment, due to the overlap of flap 17 and wall 13. By applying a generally C-shaped coupling member 28 to the ends of rims 22 and 23, they are brought into exact alignment, and are permanently secured together 35 so as to form endless reinforcing beads at both the top and the bottom of the container, which imparts rigidity to the unit.

Bottom flanges B1—B4, inclusive, are then bent inwardly, as shown in Figures 2 and 6, and bottom member 15, having rounded corners 29, is inserted from the top and secured in place on the flanges by fasteners 31 or the like. The bottom is preferably made of heavier weight material than the sides, to give it sufficient strength to sustain heavy loads.

Bottom 15, being a separate element, may be made of heavier material than the side walls, and also may be dimensioned as seen in Figure 2 so that its outer edges overlie rim 23. These features contribute to make the bottom extremely strong and able to adequately support heavy articles such as beer bottles and the like. Also, securing the bottom to flanges running along the four sides of the container strongly reinforces the sides against collapsing tendencies.

As seen in Figures 1 and 2, the flanges running along the top and lower edges of the container preferably terminate short of the rounded corners, so that the latter may be smoothly formed without binding tendencies and will retain their shape.

Top 14 is preferably provided with a flange 32, which is secured to flange T3 by a plurality of staples 33, the latter performing the dual purpose of securing the top to the container and also rigidly securing the three layers of material at the top edge of the container together to form an extremely stiffened hinging zone. Cover 14 is also provided with a pair of parallel score lines 34 and 35, so that it may be folded through approximately 180°, into the dotted line position shown in Figure 2. A further important feature is to so dimension cover 14, that when the container is closed the cover will lie in the dotted line position 36, as shown in Figure 2, below rim 22, the

latter holding it in place against inadvertent opening movement. The cover is also provided with an opening 37, and is sufficiently flexible so that a finger may be inserted and the cover bowed sufficiently to bring its free edge past rim 22. If desired, the width of the cover may also be slightly greater than the distance between the rim 22 of the end walls 11 and 13, so as to be yieldably retained in place below it in a similar manner.

Seen in Figure 3, hand opening 21 is preferably formed by striking a flap 38 from the body of walls 11 and 13 and folding it inwardly so as to lie behind flange T2. Flap 38 may be secured in place by fastening elements passing through the three thicknesses of the material, to form an extremely strong means for handling the container when loaded. If desired, an additional metal clip 39 of C-shape in section may be clamped in place as seen in Figure 3 to form an even stronger joint.

In Figure 8 there is disclosed a modified form of top construction which may be used in place of one shown in Figures 1 and 2. In this instance closure 14a is integrally formed with side wall 12a so that, when it is folded down and rim 22 applied, it may be brought into open position by folding it along the score lines 34a, 35a and an additional score line 41 located adjacent the rim. This construction possesses the advantage that it is not necessary to secure the cover to the container in a separate operation, but it does not of course possess quite the strength of the one shown in Figures 1 and 2.

In Figure 9 there is disclosed a modified manner of constructing the corners of the container, embodying a double thickness of material at the corners. The bottom supporting flanges B2 and B3 are provided on the blank as before, but in addition a corner blank 42 is left in place on the blank at the top and bottom of each corner, and provided with deep score lines 43 to facilitate bending it into cylindrical shape. Before folding the flanges down against the blank a slot 44 is provided between each flange 42 and its neighboring flanges. The modified construction is assembled in the same manner as the one previously described, the only difference being that the completed container embodies a flange 42 at each top and bottom corner which remains in engagement with the container walls as shown in Figure 9, and performs the function of providing two thicknesses of material within rims 22 and 23 all around the container, including the corners and may be desirable in certain instances.

Referring to Figures 10 and 11, we have disclosed the preferred form of apparatus for bending the container blank into final form. It comprises a pair of rollers 46 and 47 adapted to be moved together to clamp the container blank between them. Roller 46 is stationarily supported while roller 47 is mounted for rotation by any suitable means (not shown). The rolls are provided with grooves 48 and 49, spaced apart a distance equal to the spacing of rims 22 and 23. The pairs of grooves are so aligned and are of sufficient depth to receive the rims as seen in Figure 10 and are preferably so designed that when the rolls are brought together the walls of the grooves bear upon the rims and the surface of the rolls bear upon the container simultaneously, and yet avoid collapsing the rim during bending.

The bending operation is preferably carried out by placing the blank against roll 46; holding the latter stationary; bringing roll 47 to bear against the portion of the blank to be bent, approximately 90° in a clockwise direction from the position

5 shown in Figure 11; and then giving roll 47 a counterclockwise planetating motion about the axis of roll 46 as indicated by the arrow in Figure 11, to smoothly bend the blank and beads into curved form. By reason of the grooves in the bending surfaces, the blank is held in the proper position with respect to the rolls, and also collapse of the beads during the bending operation is avoided.

10 As seen in Figure 11, the rolling operation has been completed, providing curved walls 25 and the corresponding bends in rims 22 and 23, roller 46 having a radius of curvature substantially equal to the desired radius of curvature in the finished corner.

15 Although the bending members have been illustrated as taking the form of rollers 46 and 47, it is to be understood that roller 46 may be replaced by a member having a curved grooved surface, and roller 47 replaced by a flat plate having grooves matching those in the member, and the plate and member manipulated relatively to "wipe" the blank around the corner of the stationary member, and the appended claims are intended to embrace the invention when it assumes this form.

20 In Figure 12 there is disclosed a container of irregular hexagonal shape, especially designed for packaging articles of generally cylindrical shape with a minimum of voids between the articles and a minimum of voids between the articles and the container, which makes it possible to employ a minimum amount of material for packaging them.

25 The container is made in the same way as the one previously described except that the blank is formed to have six rather than four sides, and the shapes of the top and bottom are changed accordingly.

30 The container is provided with four walls 51, 52, 53 and 54 of equal width and a pair of wider walls 55 and 56, which are of equal width and disposed parallel to each other. An overlapping joint 57, similar to the one previously discussed in connection with Figures 1 to 7, is formed in wall 55.

35 We have found that by giving the container the shape illustrated, and providing it with rounded corners 25a, twenty-four cylindrical articles may be accommodated in a space materially smaller than if the container were given any other shape. For instance, compared with the rectangular container accommodating four rows, with six articles in each row, it cuts the material by almost 20 percent. It is also to be understood that, by following this disclosure, other unsymmetrical hexagonal containers may also be developed for economically packaging more or less than twenty-four articles, and the appended claims are intended to embrace the invention when it assumes those forms. Also, the articles may be stacked two or three high and the advantages of the hexagonal container still fully utilized.

40 In Figure 13 and 14 are disclosed further modified top and bottom closure constructions of the invention. In Figures 13 and 14 the upper and lower edges of the container side walls terminate in straight edges and the beads are applied after the container is set up, in a manner to be hereinafter discussed in connection with Figures 16 and 17.

45 After the container is set up and staples 27 applied to hold flap 17 in position, a bottom member 15a, cut away to provide rounded corners

61, and four flaps 62, is inserted in the bottom of the container into the position shown in Figures 13 and 14, and rim 23a is then applied, so as to firmly clamp flaps 62 against the inner surfaces of the container side walls. This securely holds the bottom in place, results in rounded corners without causing a pucker, and yet provides a double thickness of material along the four sides of the container.

It is to be understood that the closure constructions of Figures 13 and 14 may be used at the top and/or bottom of the container. When used at both the top and bottom, the container bottom will first be secured in place, the container will then be turned upright and loaded with its contents and the top then secured in place, either by a rimming operation, as shown in Figures 13 and 14, or by a stapling or stitching operation. If it is not desired to permanently secure the top in place, the closure constructions of Figures 1 and 8 may be used in combination with bottom closures constructed in accordance with Figures 13 and 14, as for instance when used in returnable beverage bottle service.

In Figure 15 we have shown a modified top closure construction split into two sections 65 and 66, and having deep flanges 67 and 68, respectively. Closures 65 and 66 may be hingedly secured to the container in the manner shown in either Figure 1 or Figure 8, and the flanges are designed to divide the contents of the container into two equal parts. For instance, if it is a bottle container, flanges 67 and 68 will fit down between the necks of the bottles, dividing them into two equal parts and making it possible to open one-half of the container at a time without disturbing the remaining bottles. Also, the flanges provide a stiffened zone extending down the middle of the container, when the latter is closed, materially adding to the rigidity thereof.

Although the blanks preferably have the rims applied thereto prior to setting them up, as shown in Figure 7, for instance, when they are to be shipped some distance and the customer is not equipped to apply beads, under some circumstances it is desirable to apply the rims at the time of setting up the container, and in Figures 16 and 17 we have shown one way in which it may be carried out.

The blank, without beads 22 and 23 of Figure 7, is folded up into container form, and staples 27 applied to secure flap 17 in place over side wall 13, as previously described. The top and bottom edges of the container are then successively passed between a pair of rolls 69 and 71 so as to crimp a metal strip in place thereon. The strip is bent into C-shape in cross-section, so as to tightly grip the side walls, and is simultaneously circumferentially curved around the container to provide closed rim 23b, having its ends overlapped at 72, and tightly gripped together. This eliminates the need for coupling members 28 used in Figure 1 and provides endless beads at both the top and bottom edge of the container side walls. The container may then be completed by applying top and bottom closures of the desired character. The rounded corners in all forms of the containers disclosed make it possible for the rim or bead to be smoothly curved around them, whereas if sharp corners are used the rimming operation would be difficult if not impossible to carry out.

It is accordingly apparent that we have provided novel low cost containers of light weight and yet comparatively great strength and which

may be shipped in knocked down state and set up and completed by the user in one of two ways, either of which results in a sturdy container for the packaging of comparatively heavy materials of all kinds, among which may be mentioned beverage bottles or cans, canned goods, cartridge or shell cases and also rectangular articles of various kinds.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

20 What is claimed and desired to be secured by United States Letters Patent is:

1. A container having a plurality of side walls and a bottom, said side walls being formed of a single length of sheet material bent transversely at a plurality of longitudinally spaced regions to form a multiplicity of side walls, each pair of adjacent side walls being joined by a curved corner, and said length of sheet material having its ends secured together, the bottom edges of certain of said side walls having inwardly directed flanges which extend along the edges of said certain side walls toward, but terminate short of, said curved corners; and means for securing said bottom to said flanges.

2. A container having a plurality of side walls and a bottom, said side walls being joined by corners of parti-cylindrical form, and being made from a single length of sheet material bent transversely into side wall and corner portions, the lower edges of said side walls each having a flange folded back upon itself and terminating at its ends short of said parti-cylindrical corners; and a reinforcing bead extending substantially continuously along and secured to the lower edges of said side walls and forming a reinforcing bead; and means for securing said bottom to said flanges.

3. The container construction defined in claim 2, wherein said bead is of C-shaped form in transverse section and has its opposite edges tightly gripping the side walls of said container and said flanges.

4. In an article of manufacture, a container of box-like form, comprising a plurality of upright side walls; a bottom; and a top, said side walls being formed of a single length of material bent transversely at a plurality of longitudinally spaced regions to form said side walls and having its ends overlapped and secured together, to provide a container having a plurality of flat side wall portions joined by curved corner portions; a strip of reinforcing material extending along and secured to the upper edges of said side walls and said corner portions; a strip of reinforcing material extending along and secured to the lower edges of said side walls and said corner portions, said strips forming marginal reinforcing beads at the top and bottom of the container; a bottom closure member; and means for securing said closure member to said container spaced above the level of the lower edges thereof, comprising means extending along each of said side walls interiorly thereof and having zones of securement to said closure member extending along and parallel to the margins of said closure member, said

zones of securement terminating at each end short of said curved corner portions, whereby said closure member is secured to said side walls and is free from securement to said curved corner portions.

5. A container having a side wall and a closure for one end of the container, said side wall comprising at least one sheet of flexible material bent into hollow form to define the container side wall; a metal reinforcing bead extending around one edge of said side wall at one end of said container and rigidly secured thereto, said bead being of generally C-shape in cross-section and enclosing said one edge of said side wall, said bead also forming an inwardly projecting marginal shoulder around said one end of the container; a plurality of flaps extending along said one edge of said side wall interiorly of said container and being tightly gripped by one longitudinal edge of said reinforcing bead, said flaps being bent outwardly from the plane of said side wall immediately adjacent said one longitudinal edge of the bead, so as to form flanges projecting inwardly from the inner surface of the container side wall in overlying engagement with the marginal shoulder formed by the bead; and means for securing said closure to said flanges, said closure seating directly upon said flanges and extending outwardly in sufficiently close proximity to said container side wall as to marginally overlie said

marginal shoulder, whereby any outward forces acting upon said closure are transmitted directly to said bead.

6. In a container having a one-piece side wall and a separate closure for one end of said container, a blank for manufacturing said container comprising a single length of flexible, fibrous sheet material having a length approximately equal to the perimeter of the container side wall and adapted to be bent into hollow form and have its ends secured together to form the entire side wall of the container; a metal reinforcing bead extending continuously along substantially the entire length of one longitudinal side edge of said blank and being rigidly secured thereto, said bead being of generally C-shape in cross section and enclosing said one side edge of said blank, said blank also embodying a plurality of longitudinal flaps lying flat against one side of the blank along one edge of said blank and being tightly clamped against the blank by one longitudinal edge of said reinforcing bead, said flaps being adapted to be bent outwardly from the plane of said blank so as to form flanges projecting inwardly from the inner surface of the container side wall after the blank has had its ends secured together, to provide supports for said container closure.

KIMBERLY STUART.
ALLEN B. WILSON.
